EDGE-FOLDING GUIDE FOR SEWING MACHINES

Josef F. Palme, Elizabeth, N. J., assignor to The Singer Manufacturing Company, Elizabeth, N. J., a corporation of New Jersey

Application October 19, 1938, Serial No. 235,723

4 Claims. (Cl. 112—147)

This invention relates to sewing machines and more particularly to improvements in edge-folding attachments adapted for use on overseaming machines of the cup-feed type, such as disclosed, 5 for instance, in the U. S. patent to R. L. Plumley, No. 1,891,605, dated Dec. 20, 1932.

One of the objects of the present invention is the provision of means applicable to a cup-feed sewing machine for producing an edge-fold or 10 hem of uniform width in a body-material, and particularly an edge-fold or hem having a certain degree of uniformity and quality in its finished state.

Another object of the present invention is to 15 provide, in an overseaming machine, a work-guiding attachment adapted to effectively control the work to a point beyond the line of needle reciprocation, whereby the stitches will not appreciably distort the body-material.

With the above and other objects in view, as 20 will hereinafter appear, the invention comprises the devices, combinations and arrangements of parts hereinafter set forth and illustrated in the accompanying drawings of a preferred embodiment 25 of the invention, from which the several features of the invention and the advantages attained thereby will be readily understood by those skilled in the art.

In the accompanying drawings, Fig. 1 is a top 30 plan view of a portion of a conventional cup-feed sewing machine embodying the present improvement.

Fig. 2 is an enlarged fragmentary view of a 35 portion of Fig. 1, showing the manner in which the stitches are formed about the folded edge of the body-material.

Fig. 3 is a front elevation of the present improvement.

Fig. 4 is a perspective view of the present improvement, illustrating clearly the relative positions of the various elements of the attachment.

Fig. 5 represents a vertical section taken along the line 5—5, Fig. 3.

Fig. 6 represents a vertical section taken along 45 the line 6—6, Fig. 3.

Figs. 7, 8 and 9 are perspective views of each of the elements of the attachment, showing clearly their details of construction.

Fig. 10 is a fragmentary view of a body-material having applied thereto an edge-finishing seam produced by a cup-feed machine fitted with the present improvement.

Referring more specifically to the drawings, the invention is disclosed as embodied in a Singer 55 Class 176 cup-feed machine comprising a frame 1

having journaled therein a horizontal reciprocating needle-bar 2 carrying needle 3 cooperating with a looper 4 in the formation of overedge stitches which are formed about the edge of a body material M fed through the machine by the usual feed-cup 5 opposed by a spring-biased presser-member 6.

Fixed in the machine frame 1 is an attachment-supporting rod 7 having fastened thereto at its free end my improved edge-folding attachment 10 8. The edge-folding attachment comprises essentially three sheet-metal members, 9, 10 and 11, arranged in stacked relation upon the supporting rod 7 and secured thereto by clamp-screws 12. The lower member 9, which is disclosed in Fig. 8, 15 preferably comprises an inverted L-shaped section of which the vertical limb portion 13 is extended toward the delivery end of the attachment and formed into a work-folding scroll 14 terminating in a stitch-finger 15 about which the 20 stitches are formed. Depending from the work-folding scroll 14 is an apron 16, flared at its lower end to facilitate the introduction of work into the attachment and to prevent the contact of the work with the presser-member 6. The horizontal 25 limb portion 17 of the inverted L-shaped section is provided with apertures 18 through which extend the clamp-screws 12.

The intermediate member 10, which is clearly 30 illustrated in Fig. 7, is preferably substantially U-shaped, as at 19, one limb 20 of which is likewise extended toward the delivery end of the attachment providing an attenuated work-supporting finger or arbor 21 about which the body-material is folded by the scroll 14. Depending 35 from the arbor 21 substantially midway its ends, is an apron 22 flared at its lower end reversely of apron 16, the two aprons 16 and 21 providing a substantially vertical passageway for the body-material M, whereby the same is prevented from 40 contacting the machine parts which may or may not be fouled with oil. This passageway further insures that the body-material is properly fed into the attachment. Similarly to the lower member 9, the intermediate member 10 is formed 45 with a lateral flange 23 apertured as at 24 to receive the clamp-screws 12.

In order to control effectively the amount of body-material used in the edge-fold there is provided an upper or edge-guiding member 11 50 secured in adjusted position preferably by one of the clamp-screws 12, as shown in Fig. 4. The upper member is formed at one end with a depending lip 25 which is normally disposed within the U-shaped portion 19 of the intermediate 55

member 10, and at its other end with an upstanding ear 26 which may be grasped by the operator to facilitate shifting of the edge-guiding member 11 when the clamp-screw is loosened. It will be seen in Fig. 9 that the provision of the enlarged aperture 27 provides for adjustment of the edge-guiding lip 25 toward and from the arbor 21, thereby to control the amount of body-material used in the edge-fold.

10 In the operation of the machine it will be understood that the attachment is supported so that the stitch-finger 15 of the work-folding scroll 14 projects above the reciprocatory needle 3, whereby it functions to prevent the stitches S, Fig. 2, from being set too tight, and thereby insures the production of an edge-fold having a very smooth appearance. It will be observed also that, with the present attachment, the body-material is under control to and slightly beyond the 20 point at which the needle 3 penetrates the same. Obviously this control of the work is desirable and particularly so when stitching flimsy materials, such as silk and the like.

The machine disclosed is particularly adapted 25 for edge-finishing handkerchiefs which are fed through the machine with the body-material in a substantially vertical position between the feed-cup 5 and the opposed presser-member 6.

While I have illustrated and described the preferred embodiment of my invention, it is obvious 30 that minor changes in the details of construction and the arrangement of the parts may be made without departing from the spirit of the invention as set forth in the appended claims.

35 Having thus set forth the nature of the invention what I claim herein is:

1. An edge-folding attachment for overseaming sewing machines comprising an arbor and a scroll member adapted to fold a body-material about 40 said arbor, said scroll member terminating in a stitch-finger about which the edge-fold-securing stitches are formed as the body-material is advanced through the attachment, and means including spaced aprons projecting from said arbor

and said scroll members providing between them a work-directing passageway insuring proper entrance of the body-material into the attachment.

2. An edge-folding attachment for sewing machines comprising a plurality of members arranged in stacked relation, the lower member comprising an inverted L-shaped section having one limb thereof extended and formed into a work-folding scroll, a second member substantially U-shaped at one end and terminating in an arbor adapted to cooperate with said scroll, and an upper member provided with means for guiding one edge of a body-material as it is fed through the attachment.

3. In an overseaming machine, the combination, with stitch-forming mechanism including a reciprocatory needle, and work-feeding means including a feed-up for advancing the work through the machine in a substantially vertical position, of an edge-folding attachment disposed in advance of the work-feeding means, said edge-folding attachment including a work-folding scroll-member disposed closely above said feed-up and terminating in a stitch-finger overlying the line of reciprocation of the needle, and a second member providing an attenuated arbor extending within said scroll-member and adapted to cooperate therewith in hem-folding the marginal edge of a body-material.

4. An edge-folding attachment for sewing machines comprising a plurality of members arranged in stacked relation, one of said members comprising a substantially U-shaped section having one of the limbs thereof terminating in a lateral supporting flange and the other limb thereof terminating in an arbor, and another of said members comprising an inverted L-shaped section having one of the limbs thereof providing a lateral supporting flange and the other limb thereof terminating in a work-folding scroll arranged in cooperative relation with said arbor.

JOSEF F. PALME.
